DESIGN FOR A COMBINATION BILL CLIP
AND COIN HOLDER OR THE LIKE

Miriam Lampl Ornsteen, New Rochelle, N. Y.

Application August 11, 1944, Serial No. 114,833

Term of patent 14 years

(Cl. D74—2)

To all whom it may concern:

Be it known that I, Miriam Lampl Ornsteen, a citizen of the United States, residing at New Rochelle, county of Westchester, and State of New York, have invented a new, original, and ornamental Design for a Combination Bill Clip and Coin Holder or the like, of which the following is a specification, reference being had to the accompanying drawing, forming a part thereof.

tion bill clip and coin holder, embodying my new design.

I claim:

The ornamental design for a combination bill clip and coin holder or the like, as shown.

MIRIAM LAMPL ORNSTEEN.
